INDUCTIVE HEATING COIL

Harold G. Frostick, Pittsburgh, and Elvyn M. Sollie, Saxonburg, Pa., assignors to Westinghouse Electric Corporation, East Pittsburgh, Pa., a corporation of Pennsylvania

Application October 31, 1942, Serial No. 464,042

5 Claims. (Cl. 219—13)

Our invention relates to inductive heating-coils, and particularly to such coils which are utilized to heat a rapidly moving, long, thin, flat metal strip, or one or more wires, or other elongated member which is moving axially through the heating coil. In many inductive heating-coils of this nature, where very high power must be put into the coil, the voltage of the coil may be a distinct limitation as to its design, and particularly the maximum voltage appearing between the coil-terminals and the metal strip or other work to be heated, within the coil.

For the most efficient operation, the diameter of the coil, or the cross-sectional area which is embraced within the inner periphery of the coil, should be as small as possible, particularly when the work to be heated is non-magnetic; and heretofore the coil has been either wound directly on an insulating liner or guide-member for the strip, wire, or other work to be heated, or when removable liners have been utilized, the space between the liner and the inner periphery of the coil has been made as small as practicable. While this sort of construction is satisfactory for many low-power and medium-power coils, it is not at all satisfactory for high-power work, as when the coil is to be supplied with several times as much power as the largest radio broadcasting station in the United States. When a very large amount of oscillation-frequency power is supplied to an inductive heating-coil, means must be provided for preventing corona or space-current discharges at the work to be heated, as a result of the electrostatic field-stress between the work and the high-voltage portions of the coil. This difficulty has been met, heretofore, by shielding-means, with the result that no small amount of difficulty has been experienced with the shielding means which has been introduced for the purpose of eliminating corona from the work to be heated.

In accordance with our present invention, we provide a design in which, in general, corona-shielding means are avoided altogether, or even if they are necessary, their design is very greatly facilitated by the reduction which we are enabled to effect in the electrostatic field-intensity in the vicinity of the liner or guide-means which is disposed close to the work being heated, within the inductive heating-coil. Our invention takes advantage of the fact that the specific inductive capacity or dielectric constant of any available solid insulator which can be utilized for the liner or separating means is several times higher than unity, that is, several times that of air or a gaseous medium. Hence, if a solid insulating or

dielectric material is disposed between the inner periphery of the coil and the inside of the liner or guide-means which is liable to be contacted by the work to be heated, the major portion, or a rather large portion, of the total electrostatic stress may be concentrated in the small airspace between the inner surface of the liner and the surface of the work which is being heated, thus setting up severe electrostatic stresses at this point, which will cause corona if the voltage is not quite low.

In accordance with our present invention, we avoid this difficulty by utilizing only a relatively thin insulating liner or separating-means, only 15 thick enough to have the mechanical strength necessary for guiding the moving strip, wire, or other work to be heated; and we make our inductive heating-coil larger than the liner, so that there is an air-gap of at least one-eighth to one-quarter of an inch, or other suitable distance, 20 usually more than a quarter of an inch, between the outer periphery of the liner and the inner periphery of the coil. With this construction, almost all of the drop in the electrostatic field-potential, 25 between the coil and the strip or work, occurs in this airgap, because of its low dielectric constant of approximately unity, whereas only a relatively small potential-difference exists between the inner and outer surfaces of the liner, because of the 30 higher dielectric constant of the liner. As a consequence of this construction, a high electrostatic field-stress does not exist between the inner surface of the liner and the outer surface of the strip or work, so that corona is, in general, prevented, or 35 if it still exists, the problem of shielding it is very considerably reduced by reason of the reduced electrostatic stresses which we obtain at our liner, by using the air-gap spacing between the liner and the coil.

40 While our invention is not limited to any particular application, the special design of coil which we have introduced appears to find its most important present application in the tinplate-flowing apparatus which is described and claimed in 45 an application of Glenn E. Stoltz and Robert M. Baker, Serial No. 464,040, filed October 31, 1942, and assigned to Westinghouse Electric Corporation.

In this application of our invention, a miles- 50 long, thin, flat, electrolytically tinplated steel strip, having a gauge usually of the order of 0.008 to 0.011 inch, and having a width of from 28 to 36 inches, is passed at a speed of the order of eleven or twelve miles per hour through an inductive heating-coil, which is required to heat 55

the strip some 300 or 400° F. within as short a distance as possible, or at least within a distance which is within a reasonable factor of safety of the distance which would produce buckling of the strip as a result of the strains therein, from thermal expansion, exceeding the elastic limit or yield point of the strip. This high rate of heat-input into the strip is needed in order to make it possible to heat-treat the plated strip in the same "line" or manufacturing process in which the strip is electroplated, dried, heated, quenched, cleaned, and otherwise treated.

The heating is for the purpose of raising the tinplate to or slightly above, its melting point, which is 452° F., so that the surface-tension of the molten tin will cause it to flow evenly over the steel, producing a solid, non-spongy, uniform texture, and making it possible to obtain as good a corrosion-resistant, shiny coating, with a tinplate only 30 millionths of an inch thick, as was previously obtained with a tinplate of three times that thickness, as applied by the old hot-dip process. The high concentration of heat, along a relatively small length of the strip, is needed in order to make it possible to heat-treat the strip in the same "line" in which it had been electroplated, so that separate manufacturing operations will not be needed; and the use of induction heating is necessary in order to be able to get enough heat into the strip in a small space, to make the strip-heating substantially independent of slight variations in gauge, to avoid physical contact with the easily marred tin surface, and to provide the high-speed heat-input control which is necessary for satisfactory operation on these high-speed tinning lines.

Our present invention provides what appears to us to be the most satisfactory, or one of the most satisfactory, coil-designs which is capable of handling the high-power concentrations which are required of the work just described.

Our invention consists in the apparatus, combinations, systems, parts and methods herein-after described and claimed, and illustrated in the accompanying drawing wherein:

Figure 1 is a diagrammatic view of circuits and apparatus embodying our invention, with our inductive heating-coil shown in section, looking edgewise on the strip or work to be heated; and

Fig. 2 is a similar view showing a modified form of coil-support.

We have illustrated our invention as applied to the inductive heating of a thin magnetizable metal strip 1, which is shown edgewise in the drawing, and which is continuously moving downwardly, in the direction of its length, at the rate of 1000 feet per minute, more or less, within an inductive heating-coil 2 which comprises a plurality of turns of a hollow conductor, wound in a single layer, through which cooling-water or other coolant is circulated, as by means of a grounded water-inlet 3 at the midpoint of the coil, and insulated water-outlets 4 and 5 at the coil-terminals 6 and 7, respectively, which are supplied with a heavy high-frequency current from an oscillation-generator 8.

A solid insulating separating-means 10 is disposed within the coil 2, with portions of said separating-means on opposite sides of the strip 1 or other work to be heated. The solid insulating separating-means 10 is preferably in the form of a flattened tubular liner of asbestos or a molded composition-product having woven glass reinforcement layers embedded therein to

provide a strong solid mass, said liner having an axially extending opening therethrough for accommodating the strip 1 or other work to be heated. If desired, the entrance-lip of the separating-means or liner 10 may be provided with a rubber guide-means 11 for guiding the strip 1 without scratching it, sufficient clearance being provided for avoiding excessive friction with the strip, or, if practicable, to avoid any contact with the strip in normal operation, although an occasional light contact is frequently permissible.

It is an essential feature of our invention that a space shall be provided between the inner periphery 12 of the coil and the outer periphery 13 of the liner 10, this space being occupied by substantially nothing but air or other gaseous ambient medium, particularly at the ungrounded or high-voltage portions of the coil, so as to provide an air-gap of at least one-eighth to one-quarter of an inch, or such other spacing, usually more, as may be necessary in any particular application.

Any suitable means is provided for supporting both the insulating liner 10 and the coil 3 with a sufficient amount of rigidity. In the form of our invention shown in Fig. 1, an outer insulating housing 16 is provided, in spaced relation around the coil 2, and the outer peripheries of the coil are supported, at a plurality of points, by pin-type insulators 17, extending radially between the coil and the outer insulating housing or supporting-means 16.

Preferably, both the liner 10 and the outer housing 16 extend beyond the ends of the coil 2; and annular end-closure means 18 and 19, of suitable insulating material, are provided for joining the liner 10 and the housing-member 16 at each of the respective ends, and to cooperate with the housing-member and the liner to provide a complete enclosure for the coil 2, while at the same time supporting the ends of the liner 10. In many cases, it is quite desirable that the enclosure-means for the coil shall be dustproof, so as to shield the coil from accumulations or condensations of tin-dust, or steam, or any other foreign matter which may tend to cause a breakdown of the coil. At the same time, the annular end-closure means, 18 and 19, provide excellent supporting-means for the liner 10, disposed a considerable distance beyond the axial extent of the coil 2, where the alternating magnetic field of the coil is relatively weak.

In the form of our invention which is shown in Fig. 2, instead of utilizing the outer housing-member 16 and the pin-type insulators 17 extending inwardly therefrom, we embed the outer periphery of our coil 2' in a solid insulating member 20 of asphalt, casting resin, or other suitable molded insulating material, which rigidly holds the coil in place, while leaving the inner periphery 12 of the coil-turns substantially free of any material amount of solid insulation. In other respects, the design shown in Fig. 2 is similar to that shown in Fig. 1.

In operation, as previously indicated, the air-gap which is provided between the liner 10 and the coil 2 or 2' provides a space in which most of the electrostatic stress between the coil and the strip or work 1 is consumed, thus materially reducing the electrostatic field-concentration in the vicinity of the liner 10, usually reducing this electrostatic field to the point where corona is not obtained on the strip or work 1. If corona should be obtained in any case, this phenomenon can

be avoided by redesigning the coil so as to have a larger air-gap between the coil and the liner, either making the air-gap larger all over, or only at the edges of the strip, or at the ends of the coil, where corona may be present. It has been found that when the strip 1, or work to be heated, is magnetizable, the coil can be enlarged so as to provide quite a large air-gap between the liner and the coil, without excessively reducing the heating-efficiency or the proportion of the coil-flux which threads the work, so as to produce eddy-currents therein.

While we have illustrated our invention in two different forms of embodiment, which are at present preferred by us, we desire it to be understood that our invention is not limited to these particular forms. We desire, therefore, that our claims shall be accorded the broadest construction consistent with their language.

We claim as our invention:

1. An inductive heating apparatus operable in a gaseous medium at approximately atmospheric pressure and comprising an induction heating-coil comprising a plurality of turns of a flowing-fluid-cooled conductor, wound in a single layer, a coil-supporting means disposed outside of the outer periphery of the coil and extending outwardly from the outer periphery of the coil for supporting the coil, the portions of the coil-supporting means which are disposed closest to the attachment-point to the coil, and for a considerable radial distance out therefrom, being substantially altogether of insulating material, a solid insulating liner disposed within the coil and having an axially extending opening therein for accommodating the work to be heated, the outer periphery of the liner being spaced from the inner periphery of the coil and being separated from at least the high-voltage portions of the coil essentially by a gaseous ambient medium, said liner having extended portions thereof extending axially beyond the axial length of the coil at each end, an insulating liner-supporting means, spaced axially beyond each end of the coil, for engaging said extended portions of the liner, and means for supplying such a large high-frequency current to the coil that the danger of space-current discharges from the coil to the

work to be heated, due to a high electrostatic stress, is an important consideration in the design.

2. The invention as defined in claim 1, characterized by said coil-supporting means comprising a housing-member surrounding the coil in spaced relation around the outer periphery of the coil, and a plurality of relatively long, spaced insulators connected at a plurality of points to the outer peripheries of a plurality of the turns of the coil for supporting the outer periphery of the coil from said housing-member.

3. The invention as defined in claim 1, characterized by said coil-supporting means comprising a housing-member surrounding the coil in spaced relation around the outer periphery of the coil, and a plurality of relatively long, spaced insulators connected at a plurality of points to the outer peripheries of a plurality of the turns of the coil for supporting the outer periphery of the coil from said housing-member, said housing-member and said liner both having an axial extent greater than that of the coil, and said liner-supporting means comprising end-closure means joining said liner and said housing-member at each of the respective ends thereof to cooperate with the housing-member and the liner to provide a complete enclosure for the coil.

4. The invention as defined in claim 1, characterized by said coil-supporting means comprising a solid mass of insulating material in which the outer portions of the coil-turns are embedded, leaving the inner periphery of the coil-turns substantially free of any material amount of solid insulation.

5. The invention as defined in claim 1, characterized by said coil-supporting means comprising a solid mass of insulating material in which the outer portions of the coil-turns are embedded, leaving the inner periphery of the coil-turns substantially free of any material amount of solid insulation, and said liner-supporting means comprising end-closure means joining said liner to said solid mass of insulating material to provide a complete enclosure for the coil.

HAROLD G. FROSTICK.
